United States Patent

Des. 239,867
Patented May 11, 1976

239,867

RADIO

Shogo Imai, Osaka, Japan, assignor to Sharp Kabushiki
Kaisha (Sharp Corporation), Osaka, Japan

Filed Nov. 30, 1973, Ser. No. 420,376

Term of patent 14 years

Int. Cl. D14—03

U.S. Cl. D56—4 B

FIG. - 1

FIG. - 2

FIG. - 3

FIG.-4

FIG.-5

FIG.-6

FIG.-7

FIG. 1 is a front, top and right side perspective view of a radio showing my new design;

FIG. 2 is a front elevational view with the strap omitted for convenience of illustration;

FIG. 3 is a top plan view thereof;

FIG. 4 is a right side elevational view thereof;

FIG. 5 is a left side elevational view thereof;

FIG. 6 is a bottom plan view thereof; and

FIG. 7 is a rear elevational view thereof.

I claim:

The ornamental design for a radio, as shown and described.
